EMIL STAHL, OF EAST STROUDSBURG, PENNSYLVANIA.

WEFT STOP-MOTION FOR LOOMS.

1,102,610.

Specification of Letters Patent.

Patented July 7, 1914.

Application filed September 16, 1913. Serial No. 790,005.

To all whom it may concern:

Be it known that I, EMIL STAHL, a subject of Germany, residing at East Stroudsburg, in the county of Monroe and State of Pennsylvania, have invented certain new and useful Improvements in Weft Stop-Motions for Looms, of which the following is a specification.

This invention relates to looms and particularly to weft stop motions for looms. In these mechanisms the so-called dagger and the element against which it impinges to throw off the power are so related and constructed that injury to one or the other—usually the dagger—frequently occurs, while occasionally the dagger fails to coact with said element in such a way as to produce the stopping of the loom. The object of this invention is, therefore, to provide a weft stop motion wherein these disadvantages will be avoided.

In the accompanying drawing, Figure 1 is a side elevation, partly in section, of a loom provided with the improved mechanism; and, Fig. 2 is a perspective view of the principal parts thereof.

In the loom frame *a* is arranged a belt-shifting or other power controlling mechanism of any suitable type, that shown—including the hand-lever *b* carried on the shaft *c* arranged to rock in the frame, the lever *d* fulcrumed in the frame and having one end suitably connected with lever *b* and the other end with the connecting rod *e* normally drawn in the direction of the arrow by the spring *f*—being one well known and in common use; the shaft *c* carries as usual the crank *g* whereby to apply the power for rocking the shaft and so destroying an interlock which, in the “set” position of the hand-lever, exists between said hand-lever and lever *d* and against the tension of the spring *f* maintains the belt on the driving pulley of the loom.

In the bracket *h* attached to the batten *B* are fulcrumed the dagger *j* and weft-fork *k* connected by the link *l*, these parts being alternately moved to clear the weft-fork from the shuttle's path and allow it to be depressed, as the batten assumes the backward position and moves forward, respectively, under the influence of the usual governing rod *m* which is suitably guided in the

batten structure and so supported in the loom frame as to rock with the batten, all in a well-known manner.

n is the usual rock-shaft journaled in suitable brackets *o* in the breast-beam *A* and carrying a cam *p* which, when the rock-shaft is turned, impinges against the crank *g* and so rocks shaft *c* to disestablish the interlock between levers *b* and *d* and thus bring about the shifting of the belt from the driving to the idle pulley.

Referring, now, to the novel features shown in the drawing as going to make up my invention, penetrated by and revoluble on the rock-shaft *n* is a lever *q* having an upwardly projecting arm *q'* and a downwardly projecting arm *q''* that forms with the rear curved face *q'''* of the lever a transverse cross-sectional V-shaped notch *q''''*. Attached to the lever eccentrically thereof is one end of a spring *r* that is coiled about the rock-shaft, the lever and spring being confined between two adjustable collars *s* and *t* fixed on said rock-shaft, and one end of the spring being attached to the collar *s*. As thus constructed, the mechanism shown and described operates as follows: In the “set” position of the levers *b* and *d* the arm *q'* of the lever *q* is held bearing against the back of the breast-beam, the effect of which is to bring the dagger-impact-receiving notch of said lever *q* always in a definite position relatively to the dagger. Whenever failure of weft occurs, on the ensuing forward movement of the dagger with the batten its free end (preferably formed with a double bevel *j'*) engages in the notch *q''''* of lever *q* and through the same and the spring *r* rocks the shaft *n* which, through its cam, in turn rocks the shaft *c* and so effects the tripping of lever *b* and the consequent stopping of the loom. The V-shape of the notch of lever *q* positively insures the dagger obtaining a purchase on the lever *q* that will cause a substantial turning thereof on its axis, whereas the spring *r*, made powerful enough to insure the lever's rotary movement being effectually transmitted to the rock-shaft *n*, cushions the action of the dagger and so prevents injury to the parts.

The tension of the spring *r* may be adjusted so that the spring will be under the desired degree of tension when the lever *b* is “set”

(arm q' of the lever then bearing against the breast-beam) by rotatively adjusting collar s on the rock-shaft n .

Having thus fully described my invention, 5 what I claim as new and desire to secure by Letters Patent is:

1. The combination, with a fixed part of the loom, the rock-shaft journaled therein, power controlling mechanism controlled by 10 the rock-shaft, the batten, the dagger movable in the batten and weft-controlled means for controlling the dagger, of means to transmit movement from the dagger to said rock-shaft including a dagger-impact-re- 15 ceiving member revoluble on said shaft and elastic means to cushion the rotary movement of said member on said shaft, substantially as described.

2. The combination, with a fixed part of 20 the loom, the rock-shaft journaled therein, power controlling mechanism controlled by the rock-shaft, the batten, the dagger movable in the batten and weft-controlled means for controlling the dagger, of means to 25 transmit movement from the dagger to said rock-shaft including a dagger-impact-receiving member having a dagger-impact-receiving notch disposed eccentrically of said

shaft, said member being revoluble on said shaft, and elastic means to cushion the rotary movement of said member on said shaft, substantially as described. 30

3. The combination, with a fixed part of the loom, of the rock-shaft journaled therein, a lever fulcrumed on the rock-shaft and having an arm adapted to bear against said part of the loom and a dagger-impact-receiving arm relatively opposite the first arm, a spring connecting said lever with and cushioning the movement thereof on said 40 rock-shaft, the batten, the dagger movable in the batten and against the second arm of said lever, weft-controlled means for controlling the dagger, and setable power-controlling mechanism controlled by the rock-shaft and normally holding the same in the position where the first-named arm of said lever bears against said fixed part of the loom, substantially as described. 45

In testimony whereof I affix my signature 50 in presence of two witnesses.

EMIL STAHL.
